UNITED STATES PATENT OFFICE.

BENGT M. W. HANSON, OF HARTFORD, CONNECTICUT; EINAR A. HANSON AND CLARENCE E. WHITNEY EXECUTORS OF SAID BENGT M. W. HANSON, DECEASED.

APPARATUS FOR AND METHOD OF TRUING ABRASIVE SCREWS.

Application filed November 30, 1923. Serial No. 677,632.

In my co-pending application Serial No. 675,034, filed November 16th, 1923, I have shown and described a machine for grinding gears, wherein an abrasive screw of emery or the like, and having a helical thread on its periphery, is employed for grinding the teeth of gears in a continuous operation, the machine being so arranged and constructed that the abrasive screw and gear blank are driven at proper relative speeds with the thread of the abrasive screw meshing with the teeth on the blank. The present invention is designed for truing, with precision, the thread on the abrasive screw so that it will very accurately generate the desired form of tooth on a gear blank, for instance. By the use of my improved invention, the abrasive screw, when it has become worn, may be very expediently and accurately dressed to the desired shape.

In the accompanying drawings, I have shown, for illustrative purposes, one general form of apparatus which I may employ in carrying out my invention, but it is to be understood that this showing is by way of exemplification only and is not to be construed as a limitation of the scope of the invention. Quite obviously, the machine and the methods carried out by the use thereof are susceptible of various modifications, forms and changes.

The invention accordingly consists in the features of construction, combination of elements and arrangement of parts which will be exemplified in the construction herein-after set forth, and the scope of the application of which will be indicated in the appended claims.

In said drawings:

Figure 1 is a front view of the machine; Fig. 2 is a view looking at the left hand end thereof;

Fig. 3 is a view taken substantially on line 3-3 of Fig. 1 and looking in the direction of the arrows:

Fig. 4 is a top plan view of the gearing mechanism;

Fig. 5 is a top plan view, on an enlarged scale, of the truing mechanism; and

Fig. 6 is a view similar to Fig. 5 but showing another embodiment of truing device.

Referring to the drawings in detail, *a* denotes a base or fixed bed of any suitable

construction on which is mounted a slide *b* 55 provided with a bearing *c* for a spindle *d* carrying the abrasive screw *e* to be dressed or retrued. Pivotaly mounted on the bed *a*, for rocking movement about an axis preferably parallel to that of the spindle *d*, is a 60 rocking bed *f* on which is supported, for sliding movement longitudinally of the abrasive screw *e*, a tool carriage *g* carrying a truing device *h*. The rocking bed *f* is provided at its left hand end with a rearwardly extending arm *i* on which is mounted a gear box *k* housing the driving mechanism through which the rocking bed is rocked on its fulcrum and the tool carriage *g* is longitudinally reciprocated. The truing or re-surfacing tool is here shown, by way of example, in the form of a diamond *m*, and this tool is intermittently fed transversely of the abrasive screw through suitable mechanism *l* controlled by the longitudinal reciprocating movement of the tool carriage *g*. From the brief foregoing description, it will be understood that during the operation of dressing or retruing the spiral rib or thread on the abrasive screw *e*, the diamond is repeatedly reciprocated longitudinally of the abrasive screw in accordance with the lead of the thread thereon, and the diamond is fed towards the abrasive screw each time the same is reciprocated so as to operate 85 upon successive portions of the side faces of the thread of the screw. In order that the diamond *m* will clear the abrasive screw on its return or inoperative stroke, the rocking bed *f* is rocked, as hereinafter described 90 more in detail.

In the present illustrative disclosure of the invention, the work slide *b* is mounted on ways 10 on the upper face of the bed *a*. These ways are at right angles to the axis 95 about which the rocking bed swings. This slide may be adjusted in any suitable manner, as by means of a screw 11 (see Fig. 2) which may be turned by a hand wheel 12 on the forward end of a shaft 13, there being 100 provided intermeshing gears 14 on this shaft and the screw. The spindle *d*, on which the abrasive screw to be retrued is mounted, may be driven in any suitable manner, as by means of a belt (not shown) passing about 105 a pulley 15 fixed to this spindle.

The rocking bed is supported for rocking movement in any suitable manner. By way

of example, the rocking bed may be journaled, as shown in Fig. 1, by means of ball bearings 20 on a shaft 21 supported for rotary movement by ball bearings 22 located 5 in suitable brackets 24 arising from the front corners of the bed *a*. It will be understood that there will be ball bearing arrangements 20 and 22 at each end of the bed *f*. The shaft 21, as hereinafter described in detail, 10 is driven from the abrasive screw spindle *d* in order to reciprocate the tool carriage *g* and rock the bed *f* in proper timed relation to the rotary movement of the abrasive screw. The tool carriage *g* comprises a 15 main slide 25 mounted on ways 26 for reciprocating movement on a line in parallelism with the axis on which the rocking bed is fulcrumed, and a supplemental slide 27 on the upper face of which is fixed a plate or 20 platform 28 for supporting the truing device *h*. The tool carriage *g* is reciprocated by means of a lead screw 29 which is intermittently driven in opposite directions in proper timed relation with the rotary movement 25 of the abrasive screw *e*. The supplemental slide 27 may be adjusted on the main one 25 by means of a screw 30 in order to properly adjust the diamond longitudinally 30 of the abrasive screw.

35 The truing mechanism, as will be seen most clearly from Figs. 2 and 5, includes a table 35 mounted for angular adjustment in a horizontal plane upon the plate 28, and a holder 36 mounted on the table 35 for movement transversely of the abrasive screw, and, 40 in the present case, at right angles to the axis about which the table is angularly adjustable. The plate 28 has, at its rear end, a boss 37 (see Fig. 2) forming a bearing which receives a stud or pivot pin 38 depending from the forward end of the table 35. On the lower end of this stud is screwed a nut 39 so as to hold the forward end of the truing device down. For the purpose of 45 guiding and steadyng the table 35, it may be provided on its under face with an arcuate rib 40 working in an arcuate slot 41, the center of curvature of which coincides with the axis of the pin or stud 38. The forward 50 edge of the plate 28 is curved, as shown in Fig. 5, and the table 35 is provided with a gib 42 (see Figs. 1 and 2) which receives this edge. The forward edge of the plate 28 is notched, as at 43, so as to receive a plunger 55 44 carried by the table 35. These notches will be of such number and so arranged that the tool holder 36 may be indexed to such angular positions that, when this holder is fed step by step towards the screw, the diamond 60 will be moved at an angle corresponding to the angularity of the side faces of the thread on the abrasive screw. In the present instance, two such notches are shown, these notches being so located as to permit the diamond to be moved to true the 65 thread on the abrasive screw, the faces of which are at the usual pressure angle, namely $14\frac{1}{2}$ °.

The holder 36, together with the diamond carried thereby, may be intermittently moved 70 in a direction transversely to the abrasive screw in any suitable manner, as by means of a screw 45 threaded in the holder 36 and journalled against axial movement in the table 35. On the outer end of this screw is 75 a hand wheel by means of which the diamond may be manually adjusted relative to the abrasive screw. Also associated with this screw is a ratchet mechanism, intermittently actuated by the reciprocating movement of the tool carriage *g*. In the present instance, a ratchet wheel 47 is fixed to the screw 45, and journalled on the screw is a lever, on one arm 48 of which is pivoted a pawl 49 cooperating with the ratchet wheel 47. The other arm 50 of this lever is connected by a ball and socket joint 51 to a rod 52 slidably adjustable in a block 53 connected by a ball and socket joint 54 to the upstanding leg or arm 55 of a lever 56 pivoted, as at 57, to a plate 58 secured to and movable with the main slide 25 of the tool carriage *g*. Connected to another arm 59 of the lever 56 is a follower pin 60 which is guided, for vertical movement, in a bearing 61 provided on the lower end of the plate 58. The lower end of this follower pin rides upon a guide member or cam 63 which is in the form of a plate pivoted, as at 64, for angular adjustment, and adapted to be 65 locked in any desired angular position by a screw or bolt 65. The lever 56 is normally urged in a clockwise direction, in order to maintain the follower pin 60 in engagement with the cam 63, by a spring pressed 70 plunger 66 carried by the bracket 58 and engaging another arm 67 on the lever 56.

75 It will be observed that, owing to the ball and socket joints 51 and 54, and, due to the fact that the rod 52 is longitudinally adjustable in a block 53, provision is made for permitting angular adjustment of the truing mechanism. It may be assumed that, 80 when the tool carriage *g* moves towards the right, referring to Fig. 1, the diamond *m* is moved on its operative stroke, that is, it is operating upon the abrasive screw. During this operative stroke, the lever, which carries the pawl 49, will be moved in 85 a counterclockwise direction, and the lever 56 will be urged in a clockwise direction to maintain the follower pin 60 in engagement with the guide member 63. When the tool carriage has reached the end of its operative stroke, the rocking bed *f* will be swung 90 on its fulcrum so as to withdraw the diamond *m* from the abrasive screw, and then the tool carriage will be moved to the left, that is on its inoperative stroke, and when 95 so moved, the follower pin 60 will ride up 100

105 110 115 120 125 130

- the cam 63, thereby moving the lever 56 counterclockwise, and rotating the arm 48, which carries the pawl 49, in a clockwise direction. When this pawl is thus rotated, 5 it will turn the ratchet wheel 47, together with the screw 45 on which this wheel is fixed, a predetermined amount to feed the holder 36 and diamond point carried thereby forwardly a very slight distance.
- 10 As stated, it is advisable that on the return or inoperative stroke of the dressing tool *m*, it shall be free of the work. To this end, the rocking bed may be rocked in timed relation with the longitudinal reciprocating movement of the tool carriage. In the present illustrative disclosure, this is accomplished by means of a cam 75 fixed upon a shaft 76 journaled in the gear box *k* which is mounted on the rearwardly extending arm *i* of the rocking bed. Pivoted in a bracket 77 fixed on the rear end of the arm *i* is a rocking beam 78, the long end or arm of which rests upon the cam 75 and the other or shorter end or arm of which 20 rests upon a pin 79 slidably carried by the bracket 77 and resting upon a suitable abutment 80 on the fixed bed *a*. The cam 75 is intermittently rotated through 180°. It will be observed that upon one-half revolution of this cam, the forward end of the rocking beam 78 will be lowered, permitting the rocking bed to swing rearwardly and downwardly to bring the diamond point into operative relation to the abrasive screw. 25 On the next half revolution of the cam, which occurs after the diamond point has made its operative stroke, the forward end of the beam 78 is raised, thereby swinging the rocking bed in a direction to withdraw the diamond point from operative relation to the abrasive screw so that the diamond point will be clear of the abrasive screw on the return stroke of the former.
- 30 The various mechanisms may be driven in any suitable or desired manner, but, by way of illustration, I have shown one form of drive mechanism which may be adopted to advantage. The shaft 21 is driven from the abrasive screw spindle *d* through a worm 85 fixed on this spindle, a worm wheel 86 on the shaft 87, and bevel gears 88 between the shaft 87 and the shaft 21. The upper end of the shaft 87 is carried by a bearing or housing 89 suitably journaled 35 on the spindle *d*, and one of the bevel gears 88 is splined on the shaft 87 so as to permit of rocking movement of the rocking bed *f* and transverse adjustment of the slide *b* and the parts carried thereby. Within the gear box *k* is a shaft 90 which is constantly driven from the shaft 21 through the gears 91. Fixed on the shaft 90 is a gear 92 (see Fig. 4) meshing with a gear 93 on the sleeve 94 which is normally loose on the shaft 76 40 which carries the reversing cam 75. Fixed to the shaft 76 is a cam sleeve 95 which controls the reversing clutch mechanism for the lead screw through which the tool carriage *g* is reciprocated.
- 45 Between the sleeve 94 and the cam sleeve 95 is an escapement ratchet clutch mechanism through which the shaft 76 is intermittently rotated. In the present illustrative disclosure, this mechanism includes a ratchet wheel 100 fixed to the sleeve 94 and a pawl 101 (see Figs. 2 and 4) pivoted, as at 102, to a disk 103 fixed to the sleeve 95. The pawl 101 is urged into engagement with the ratchet wheel 100 by a spring 50 pressed plunger 104 carried by the disk 103. Pivoted upon a bracket 105 fixed to the gear box *k* are a pair of pivoted levers 106 the inner ends of which are diametrically disposed relative to the ratchet wheel 100, as shown most clearly by dotted lines in Fig. 2. The outer ends of these escapement levers are, by means of spring pressed plungers 107, maintained against opposed abutments 108 upon a vertically movable rod 109 connected at its lower end to a lever 110 fixed on a shaft 111 which extends forwardly to the front of the machine. On the forward end of this shaft is fixed an arm 112 (see Fig. 1) connected by a link 113 to a lever 114 pivoted to the rocking bed. The link 113 may be connected to the lever 114, as shown in Fig. 1, when the abrasive screw is provided with a right hand thread, for instance. If an abrasive screw with a left hand thread is to be retrued, in which case it may be presumed the tool carriage should be moved towards the left on its operative stroke, the link 113 would be connected to the left hand arm 114' of the lever 114. Connected to this lever 114 is a rod 115 carrying adjustable dogs 116 with which a dog 117 on the tool carriage *g* is adapted to cooperate. 60
- 65 It will be observed that, when the tool carriage reaches the end of its operative stroke, in the present instance, its movement towards the right, referring to Fig. 1, the dog 117 on the tool carriage will strike the right hand dog 116 thereby moving the rod 115 to the right and, through the connections described, rotating the shaft 111 in a direction to lower the rod 109. When this rod is thus lowered, the upper escapement lever 106 is swung in a direction to release the pawl 101, whereupon this pawl will engage the ratchet wheel 100 causing the shaft 76 and the cam 75 carried thereby to rotate. Rotation of this shaft, however, is limited to 180° for, after the shaft has made one-half revolution, the pawl 101 strikes the lower escapement lever 106, whereupon this pawl is disengaged from the ratchet wheel 100. When the tool carriage completes its inoperative or reverse stroke, the dog 117 thereon will engage the left hand dog 116, thereby moving the rod 120
- 70

- 115
- 120
- 125
- 130

115 to the left and, through the connections described, the rod 107 will be raised, whereupon the lever escapement lever 106 will be released from the pawl 101, permitting the 5 same to engage the ratchet wheel 100. The shaft 76 will now be rotated another half revolution and then the upper escapement lever 106 will disengage the pawl 101 from the ratchet wheel.

10 The lead screw 29, by means of which the tool carriage is reciprocated, is driven from the shaft 90 in the following manner. Located adjacent the shaft 90 is a shaft 120 and between this latter shaft and the lead screw 15 are a train of gears 121. These gears are adapted to be changed so that the tool carriage may be moved in accordance with the selected pitch of the thread on the abrasive screw. Fixed on the shaft 90 are a pair of 20 gears 122, 123. The gear 122 is in mesh with a gear 124 loose on the shaft 120. The other gear 123 drives, through an intermediate gear 125 fixed on a stub shaft 126, a gear 127 also loose on the shaft 120. It will be 25 seen that the gears 124 and 127 are constantly driven in opposite directions. The clutch mechanism for alternately fixing the gears 124 and 127 to the shaft 120 may be of any suitable construction. In the present instance, this clutch mechanism includes a 30 sleeve 128 having at each end a single clutch tooth 129. The gears 124, 127 are respectively provided with a single clutch tooth 124' and 127' adapted to cooperate with corresponding clutch teeth 129 on opposite ends 35 of the sleeve 128. These parts are provided with single clutch teeth to insure uniformity in the reciprocating movement of the tool carriage. The clutch mechanism just described is controlled by the ratchet clutch 40 mechanism which, in turn, is controlled, as heretofore stated, by the reciprocating movement of the tool carriage. The sleeve 95 has a cam groove 130 in which works a pin 131 45 carried by a shipper lever 132 suitably pivoted on a stud 133. The groove 130 has an offset 130' to permit the lever 132 to be thrown into neutral position, as by means of a handle 140 on the upper end of the stud 50 133. Journalled on this stud is an arm 134 having, in its free end, a pin 135 which works in a groove 136 in the clutch sleeve 128. One end of the shipper lever 132 is provided with a pair of arms between which 55 is positioned a web or rib 137 on the arm 134. The arms of the shipper lever 132 carry spring pressed plungers 138 which respectively engage opposite sides of the rib 137. The arm 134 is provided in order to prevent 60 jamming of the parts in the event that, when the shipper lever is thrown, a tooth on the clutch sleeve 128 should strike the top of a tooth on one of the gears 124, 127.

The operation of the mechanism is briefly 65 as follows: When the abrasive screw has

become worn to such an extent that it should be retrued, it is secured to the spindle *d*. With the reversing cam 75 in such position that the rocking beam rests upon the lowest point of this cam, the slide *b* will be adjusted 70 to move the abrasive screw laterally into operative relation to the diamond point; the truing device will be properly indexed upon the plate 28 in accordance with the angularity of one of the side faces of the thread 75 on the abrasive screw; the supplemental slide 27 of the tool carriage will be adjusted by the screw 30 so as to bring the diamond point into proper relation longitudinally of the thread on the abrasive screw, and the 80 holder 36 will be manually advanced or adjusted by turning the screw 45 to engage the diamond point with the face of the thread, preferably, at a point at the outside edge 85 of this face. Assuming that the operative parts of the machine have been properly selected and set up, the machine may be thrown into operation by turning the handle 140 to proper position. The lead screw will now move the tool carriage on its operative 90 stroke during which the diamond point will take a cut on one face of the thread throughout its length. After the tool carriage is moved to the right to such extent that the diamond point is beyond the abrasive screw, 95 the dog 117 on the tool carriage will strike the right hand dog 116 on the rod 115 whereupon, through the mechanism described, the reversing cam 75 will be rotated 180° to swing the rocking bed upwardly and forwardly and thereby withdraw the diamond point from operative position and then the lead screw will be reversed to move the tool carriage on its inoperative stroke. During 100 this inoperative stroke, the cam or guide member 63 will raise the follower or pin 60 and thereby cause the ratchet mechanism associated with the screw 45 to turn this screw a very slight amount and thereby feed the diamond point one step towards the 105 abrasive screw. When the work carriage has completed its inoperative stroke, the cam 75 will again be rotated 180° whereupon the rocking bed will swing rearwardly and downwardly to bring the diamond point into 110 operative position with respect to the abrasive screw, and then the work holder will again be moved on its operative stroke, during 115 which time the diamond point will take another cut in the face of the thread just inwardly of the previous cut. This sequence of operations is repeated until one face of the thread is retrued throughout its depth. Then the truing device is angularly adjusted or indexed so that the diamond point will 120 operate upon the other side face of the screw. The outside or truncated face of the thread on the abrasive screw may be trued by very slowly moving, by means of the screw 125 30, the diamond point in a straight line in 130

parallelism with the axis of the abrasive screw.

In Fig. 6, I have shown, more or less diagrammatically, an arrangement of truing mechanism which may be employed to advantage when it is desired to true an abrasive screw having a thread with its side faces other than straight in the direction of their depth. In this figure, I have shown the abrasive screw as having a thread with double curve faces so that the abrasive screw, in outline, will correspond to a double curve rack adapted to mesh with the double curve gear to be ground. Referring to this figure, 27' designates the supplemental slide of a tool carriage; 28', the plate thereon; 35', a table; and 36', a tool or diamond point holder. In the present instance, the tool holder 36' may be moved in a direction laterally of the abrasive screw in the same manner as in the preceding embodiment. The screw 45' has a nut 150 slidable in a groove 151 in the bottom of the holder 36' so as to permit this holder to move laterally of itself under the influence of cams 152. These cams, which constitute pattern means, have their operative faces corresponding in all particulars to the shape to be given to the side faces of the thread on the abrasive screw. The holder 36' is provided with projections 153 which engage and follow the curved faces of the cams 152. The holder 36' is urged in a direction to maintain the projections 153 in engagement with the cams 152 in any suitable manner, as by means of spring pressed plungers 154 carried by the table 35'. It will be understood that, with the arrangement just described, the diamond point, after each operative stroke longitudinally of the abrasive screw, will be fed slightly inwardly towards the axis of this screw by turning the screw 45', and when the diamond point is thus fed inwardly, it will move slightly longitudinally of the abrasive screw, owing to the cams or patterns 152. When one face of the thread on the abrasive screw has been trued up in the manner just described, the pattern cams 152 are reversed and inverted so that the 50 cam surfaces thereon will take the dotted line positions shown in this figure. The other face of the thread on the abrasive screw may then be retrued. The cams 152 are diagrammatically shown as being held in position by suitable screws 156 and lugs 157.

As many changes could be made in the above construction and many apparently widely different embodiments of this invention could be made without departing from the scope thereof, it is intended that all matter contained in the above description or shown in the accompanying drawing shall be interpreted as illustrative and not in a 60 limiting sense.

I claim as my invention:

1. In combination, means for rotatably supporting an abrasive screw, a tool for truing the thread on said screw, and means for repeatedly and relatively moving said tool and abrasive screw longitudinally of the axis of the latter and in accordance with the lead of the thread thereon with said tool engaging a side face of said thread at successive points in the direction of its depth. 75

2. In combination, means for rotatably supporting an abrasive screw, and diamond point for truing the thread on said screw movable longitudinally of said screw in accordance with the lead of the thread thereon 80 and intermittently movable laterally of the screw in accordance with the shape of the faces of said thread.

3. In combination, means for rotatably supporting an abrasive screw, a tool for 85 truing the thread of said screw, means for repeatedly moving said tool longitudinally of the abrasive screw in accordance with the lead of the thread thereon, and means for intermittently moving said tool laterally of 90 the screw in accordance with the angularity of the side faces of the thread thereof.

4. In combination, means for rotatably supporting an abrasive screw, a diamond for truing the thread of said screw, means for 95 repeatedly moving said diamond longitudinally of the abrasive screw in accordance with the lead of the thread thereon, and automatically actuated means for moving said diamond with a step by step movement 100 along the faces of the thread in the direction of their depths.

5. In combination, means for rotatably supporting an abrasive screw, a tool for truing the thread of said screw, means for reciprocating said tool longitudinally of said screw in accordance with the lead of the thread thereon, means for feeding the tool axially of said screw in accordance with the shape of the side faces thereof upon each 110 reciprocating movement of said tool, and mechanisms for operating all of said means in timed relation.

6. In combination, means for rotatably supporting an abrasive screw, a diamond point for truing the thread of said screw, means for reciprocating said diamond point longitudinally of the abrasive screw in accordance with the lead of the thread thereon, means for feeding said diamond point along the face of the thread in the direction of its depth, and means for withdrawing said diamond point from said screw upon the return movement of said diamond point. 115

7. In combination, a spindle for rotatably supporting an abrasive screw, a tool for truing the thread on said screw, means operatively connected to said spindle for reciprocating said tool longitudinally of the abrasive screw in accordance with the lead of 130

the thread thereon, means controlled by the reciprocating movement of said tool for intermittently feeding said tool along the face of the thread in the direction of its depth, 5 and means operatively connected to said spindle for withdrawing said tool from the abrasive screw upon the return movement of said tool.

8. In combination, means for rotatably 10 supporting an abrasive screw, a diamond point for truing the thread on said screw mounted for angular adjustment corresponding to the angles of the faces of the thread on said screw and movable longitudinally 15 of said screw in accordance with the lead of the thread thereon and laterally of said screw in accordance with the angles of the side faces of the thread thereon.

9. In combination, means for rotatably 20 supporting an abrasive screw, a diamond point for truing the thread on said screw, a holder for said diamond point mounted for angular adjustment whereby the same may be moved at an angle corresponding to the 25 angle of the side faces of the thread on said abrasive screw, means for reciprocating said holder to move said diamond point longitudinally of the screw in accordance with the lead of the thread thereon, and means for 30 feeding said holder in its angular positions of adjustment laterally of the abrasive screw.

10. In combination, means for rotatably supporting an abrasive screw, a tool carriage mounted for rocking movement about an 35 axis parallel to the axis of said screw, means for reciprocating said tool carriage longitudinally of the screw in accordance with the lead of the thread thereon, a tool on said tool carriage, means intermittently feeding 40 said tool on said carriage laterally of the abrasive screw in accordance with the shape of the faces of the thread, and means actuated in timed relation to said reciprocating means for rocking said tool carriage to withdraw 45 the tool from the abrasive screw on the inoperative stroke of the tool.

11. In combination, means for rotatably supporting an abrasive screw, a rocking bed arranged to swing about an axis parallel to 50 the axis of the screw, a tool carriage mounted on said bed for reciprocating movement axially of said screw, a tool holder mounted on said carriage for intermittent feeding movement transversely of the abrasive screw, 55 and a cam driven in timed relation to the reciprocating movement of said carriage for rocking said bed to withdraw the tool from the abrasive screw upon the reverse stroke of said tool carriage.

60 12. In combination, a spindle for rotatably supporting an abrasive screw, a rocking bed mounted for swinging movement about an axis parallel to the axis of said screw, a tool carriage mounted for movement on 65 said rocking bed axially of said

screw, a tool holder mounted on said tool carriage for angular adjustment in accordance with the angularity of the faces of the thread on said screw, a lead screw connected to said spindle for reciprocating said 70 tool carriage in accordance with the lead of the thread on said screw, a cam driven in timed relation with said lead screw for rocking said bed to withdraw the tool on the reverse stroke of said tool carriage, and 75 means controlled by the reciprocating movement of said carriage for feeding said tool holder laterally of said screw.

13. In combination, means for rotatably supporting an abrasive screw, a tool for 80 truing the thread on said screw, means for reciprocating said tool axially of the screw in accordance with the lead of the thread thereon, and means for moving said tool laterally of said screw on other than a 85 straight line corresponding to the contour of the side face of the thread.

14. In combination, means for rotatably supporting an abrasive screw, a tool for truing the thread on said screw, means for 90 reciprocating said tool axially of said screw in accordance with the lead of the thread thereon, and devices for feeding said tool with a step by step motion laterally of said 95 screw on an irregular line corresponding to the contour of the side face of the thread in the direction of its depth.

15. In combination, means for rotatably supporting an abrasive screw, a tool for truing the thread on said screw, means for 100 reciprocating said tool longitudinally of said screw in accordance with the lead of the thread thereon, means for moving said tool laterally of said screw with a step by step movement, and pattern means for 105 guiding said tool when it is so moved laterally in conformity to the contour of the side faces of the thread on said screw.

16. The method of truing a thread on an abrasive screw which consists in taking helical cuts in a side face of the thread at successive points in the direction of its depth. 110

17. The method of truing a thread on an abrasive screw which consists in rotating the screw and repeatedly moving a tool longitudinally of the axis of the screw in accordance with the lead of the thread thereon with said tool engaging a side face of said thread at successive points in the direction of its depth. 115

18. The method of truing a thread on an abrasive screw which consists in rotating the screw, repeatedly reciprocating a resurfacing tool axially of the screw in accordance with the lead of the thread thereon, and moving the tool laterally of the screw with a step movement upon each reciprocating movement in accordance with the shape of the side faces of the thread on the screw. 120
